**THREAD CHASERS HAVING THE LAST TOOTH
FREE OF FLANK CONTACT REARWARDLY OF
THE THREAD CREST CUT THEREBY**

John W. Kelso, Dravosburg, Pa., assignor to United States Steel Corporation, a corporation of New Jersey

Filed Oct. 30, 1959, Ser. No. 849,858

3 Claims. (Cl. 10—111)

This invention relates to improvements in apparatus for cutting tapered threads on the ends of pipe, bar or the like.

A particular object of the invention is to provide improved chaser dies for such operations characterized by identical profiles. Such characteristic reduces die cost 15 by simplifying die manufacture and greatly reduces die inventory.

A further object is to provide a die having improved cutting characteristics whereby the number of chaser dies required to effect a full thread and the threading time are 20 greatly reduced.

Another object is to provide a chaser die adapted to the use of sintered carbides and the like as the die material.

Other objects and adaptations of the invention will become apparent as the description proceeds, in which:

FIGURE 1 is a partial section through the threaded end of a pipe showing the profile of the No. 1 chaser of a set of conventional chaser dies and certain characteristics of the thread cut by such a set of conventional chaser dies;

FIGURE 2 is a schematic showing of the order, shape and certain other characteristics of the progressive cuts taken by the teeth of a set of conventional chaser dies during the formation of a single full thread;

FIGURE 3 is a partial elevation of a threading machine showing the chaser head thereof and a preferred arrangement of the improved chaser dies of the present invention therein;

FIGURE 4 is a partial section taken along the line IV—IV of FIGURE 3;

FIGURE 5 is similar to FIGURE 2 but showing the shape and sequence of cuts made by the improved chaser dies of the present invention in forming a single full thread; and

FIGURE 6 is an enlarged view showing preferred rake and clearance angles of the teeth of the improved dies.

My invention is primarily concerned with the threading of pipe 4 inches or more in diameter, commonly termed casing, tubing and drill pipe. A symmetrical tapered thread of 8, in some instances 10 threads per inch, running out at a steeper angle than the angle of taper, is used for such product. Because of rigorous service conditions, dimensions, quality and other characteristics of thread are limited by strict specifications (see API Standard 5A March 1958). Fundamental dimensions of such threads are:

Threads/inch	Taper (on diameter) (inches/foot)	Pitch	Flank angle, deg.
8.....	3/4	0.125	30
10.....	3/8	0.100	30

Depth of thread varies with the specified root and crest shape and ranges, in the case of 8 threads per inch, from 0.1083 inch sharp threads to 0.07125 inch for API round threads. The threads are usually run out at an angle of between 10° and 15°. In the art of cutting such threads it has been the practice heretofore to use a series of 6 to 12 chaser dies having the general profile indicated in FIGURE 1. Such dies are characterized by several truncated teeth 1, 2, 3 and 4 comprising a lead or runout

followed by two or more fully formed teeth 5. The crest-cutting portions 6 of all the teeth are fully formed and lie tangent to the major cone 7 of the finished thread; the fully formed root-cutting portions 8 of teeth 5 lie tangent to minor cone 9. The lead portion of the die is formed by chamfering teeth 1, 2, 3, and 4 along an angle A which is the half-apex angle of vanish cone 10 of the finished thread. Since the length of the lead teeth of each succeeding die must increase, the profiles of the dies comprising a conventional chaser set vary with their position in the set. Conventional chaser die sets produce a runout characterized by threads having fully formed crests but truncated roots. The full thread is cut from the crest downward by each succeeding tooth deepening and narrowing the cut made by preceding teeth. This action is depicted schematically in FIGURE 2 wherein for simplicity it is assumed that the thread has been cut by a single die of the form shown in FIGURE 1. Attention is directed to the fact that with the exception of the first tooth, the crest-cutting portions and an increasing length of the flanks of each succeeding tooth simply rub upon surfaces previously cut.

Conventional chaser dies are made of tool steel and the cut per tooth and the speed of threading have been strictly limited by the limitations of this material. Attempts to make the dies of sintered carbide or like materials capable of operating at higher temperatures than tool steel, and therefore at higher threading speeds, have been unsuccessful. I have found the failure of such carbide dies as well as a number of other limitations of the threading operations is largely attributable to the aforementioned rubbing action inherent in the conventional chaser dies.

FIGURES 3 and 4 show a preferred embodiment of the present invention and serve to illustrate the principles thereof. In this embodiment, threading is accomplished by two chaser dies 11A and 11B mounted in a retractable chaser head 12 of a suitable threading machine. With the exception of simplification of the chaser head 12 to accommodate only two dies, the threading machine is conventional and will not be described in detail.

As shown in FIGURE 3, die 11A is carried by the left half 12L of the head; die 11B, by the right half 12R. The two halves of the head are slidably mounted on a carriage 13 and each is urged into cutting contact with pipe P by a reversible hydraulically operated mechanism 14. Movement of each half head toward pipe P is limited by a downwardly depending bracket 15 carrying a roller 16 which bears upon a sine bar 17 fixedly attached to the main bed 18 of the machine. Carriage 13 is slidably mounted on bed 18 and moved longitudinally of the pipe by the lead screw (not shown) of the machine. Pipe P is supported and rotated by a chuck (not shown) carried by the drive head (not shown) of the machine. The gearing of the drive head and lead screw are selected as required by the pitch of the thread to be cut; the dimensions and angularity of the sine bar by the degree of thread taper desired.

As shown in FIGURE 4, chasers 11A and 11B are identical in profile. Each has four cutting teeth, numbered 21, 22, 23, and 24 from the forward face 25 of the die. The teeth are spaced one pitch of finished thread apart and each comprises a fully formed, arcuate, root-cutting portion 26 and leading and following flank-cutting portions 27 and 28, respectively. The latter are arranged at flank angles C and C' with respect to a line perpendicular to axis 29 of pipe P. In the symmetrical thread of the illustration, angles C and C' are equal and equal to the half angle of the finished thread. Root-cutting portions 26 of all the teeth are arranged to lie tangent to a line 10 opening toward the forward face 25 at a lead angle A. Line 10 defines the vanish cone of the finished thread; angle A, the half-apex angle thereof. The fol-

lowing-flank-cutting portion 28 of rearmost tooth 24 terminates in an arcuate crest-cutting portion 30 spaced from the root-cutting portion of this tooth as required to cut a finished thread of desired height and taper. The latter is indicated by angle B which is the half-apex angle of the major and minor cones 7 and 9, respectively, of the finished thread. As shown in FIGURE 4, the length of crest-cutting portion 30 is limited to that necessary to just complete the cutting of the thread crest and portion 30 is terminated in a rounded heel portion 31 at its point of tangency with the lead flank of the finished thread. This must be done to avoid deleterious rubbing and consequent damage to the thread at this point.

Dies 11A and 11B are spaced 180° apart with 11A the No. 1 chaser of the pair, a half pitch ahead of 11B. The dies are positioned in head 12 with their bases 32 in planes parallel to axis 29 of pipe P with chaser die 11B being shimmed, by spacer 33, toward axis 29 by an amount equal to the pitch of the thread times the tangent of angle A divided by the number of dies comprising the set.

As indicated by the greatly reduced number of cutting teeth, the present invention contemplates a greatly increased cutting load per tooth as well as much higher threading speeds. Accordingly, the rate of heat generation at the cutting surfaces is enormously increased and dies 11A and 11B must be made of tungsten carbide or equivalent material capable of withstanding these more rigorous service conditions. Experience has shown that the carbide dies of my invention perform best if all cutting edges are lapped to a negative rake angle S of between 12 and 30°. Further that length L of root- and crest-cutting portions 26 and 30, respectively, be no more than about 0.030 inch, with the balance of the portions lapped to provide a relief angle R of 3 to 7° as indicated in FIGURE 6. It is unnecessary to provide a helical lead to the teeth of the chasers of the present invention. Such lead, however, may be desirable in chasers for threading pipe of less than 4 inches in diameter.

The terms "pitch," "flank angle," "vanish cone," "major," and "minor cone," etc. are used herein as defined in ASME Publication ASA B 1.7-1949, "American Standard Nomenclature, Definitions and Letter Symbols for Screw Threads."

In operation, the pipe P is gripped and rotated by the drive head of the machine and chaser head 12 is advanced onto the pipe by the lead screw of the machine. Dies 11A and 11B are maintained in proper taper-cutting position by the hydraulic mechanisms 14 forcing the halves 12R and 12L of the head into contact with sine bar 17; the sides of which diverge at the desired angle of taper B. Thus as head 12 advances, the bar 17 forces 12R and L apart and the dies cut a thread tapering at angle B and running out at angle A. Upon completion of a thread of desired length, the mechanism 14 is reversed to retract the dies and the pipe discharged from the machine.

Cutting a heavily tapered thread requires pre-tapering of the pipe. This may be done externally of the threading machine or by means of suitable cutting tools mounted in the chaser head immediately ahead of the dies 11A and 11B. For the reasons which will be subsequently explained, it is essential to the purposes of the present invention that pre-tapering leave a topping of not less than .002 nor greater than .018 inch of metal to be removed by the crest-cutting portion 30 of tooth 24 of die 11B.

As illustrated in FIGURE 5 the sequence of cutting is: tooth 21 of die 11A, tooth 21 of die 11B, tooth 22 of die 11A, etc. The amount and shape of the metal removed by each tooth is indicated by the shaded area associated with each tooth. It is apparent that tooth 24 of 11B effects a transition from runout to full thread form, i.e., the crest-cutting portion 30 of this tooth lies tangent to and defines the major cone 7 while the root-cutting portion 26 thereof lies tangent to and defines minor cone

9 of the finished thread. Moreover, it is apparent that the runout thread cut by dies of the above profile and arrangement is characterized by fully formed roots. As illustrated in FIGURE 5, the full thread is cut by each tooth deepening and widening the cut made by the teeth preceding it; the crest of the thread being formed last. Accordingly, the chaser teeth of the dies of the present invention contact the pipe only in a cutting relationship, i.e., the deleterious rubbing of the teeth at the flanks and crests is completely eliminated. The importance of the latter is best illustrated by the following comparison of chaser performance in cutting API 8 threads per inch on 7-inch diameter, Long Thread, Grade H seamless line pipe:

Chaser			Life, number pieces threaded	Average, threading time per piece (sec.)
Form	Material	Dies/set		
Conventional	Tool steel	8	100	128
Do.	Tungsten carbide	8	(¹) 100	(¹) 10
Per Figure 4	do	2	(¹) 100	(¹) 10

¹ No satisfactory thread produced.

In addition to a remarkable decrease in threading time without sacrifice of die life, the chasers of my invention produce a smoother, harder thread having a considerable reduced tendency to seize in the coupling. Metallurgical examination shows the thread to be characterized by a work hardened surface about 0.001 inch in depth and about 2 points Rockwell harder than conventionally cut threads. I find it essential to my results that not less than 0.002 inch and preferably not less than 0.003 inch of metal be removed by any cutting edge of the die contacting the pipe. Cuts of several times this amount can be taken. Too heavy a cut, however, results in a roughening of the thread and I find maximum metal removal by any tooth must be limited to about 0.018 inch.

To avoid distortion of the thread by lateral pressures developing during threading, a minimum of two chasers are required angularly displaced as shown in FIGURE 3. While stability in this respect is increased by multiple chasers, the improvement afforded by more than two chasers is slight and the use of more than three chasers is incompatible with the aims of the present invention.

Within the limits of the aforementioned considerations, the choice of the depth of metal to be removed per tooth as well as the number of teeth depends largely upon the depth of the thread to be cut, flank angles thereof, the taper of thread and angle of runout desired. For example, in the preferred arrangement of two dies for cutting an API round thread of 8 threads per inch, the standard depth of which is 0.07125 inch, I prefer to use a topping of about 0.008 inch, a depth of cut of about 0.009 inch per tooth and four teeth per die. The teeth of such chasers would remove a minimum of 0.0045 inch of metal at the flanks and the resulting thread would run out at an angle of about 10°. It should be noted that with a topping of 0.008, a taper angle of 1°47', and a runout angle of 10°, the first tooth of the first die (11A) of the pair would cut to a depth of 0.0158 inch. The latter however, is well within the 0.018 maximum previously specified.

The same thread can be cut with a series of three identical chasers of three teeth each, in which case, the nominal depth of cut per tooth would be 0.008 inch, removing a minimum of about 0.004 inch at the flanks. The resulting thread would run out at about 13°56'. The second die of such series of three identical chasers must be positioned $\frac{1}{3} \times .125 \times \tan 13^{\circ}56'$ or 0.0103 inch toward pipe axis 29 and the third die thereof, an additional 0.0103 or a total of about .021 inch; the three dies are preferably spaced 120° and $\frac{1}{3}$ pitch apart in the chaser head.

While I have described my invention as applied in the cutting of the round API threads, the principles thereof are applicable to cutting of other standard threads in

5
cluding non-symmetrical threads, provided such threads have flank angles greater than

$$\cos^{-1} \frac{.002}{.018}$$

the latter limit being dictated by the aforementioned minimum and maximum depths of metal removal by any cutting surface of the dies.

Chaser dies embodying the principles outlined above can be used in any conventional threading machine comprising a chaser head adapted to receive and support the dies in threading position, means for supporting the pipe dies in threading position, means for supporting the pipe to be threaded, means for rotating the head or pipe, one relative the other, means for advancing either the head or the pipe longitudinal one of the other at a rate controlled in relation to the speed of rotation to produce finished threads of the desired pitch, and tapering means associated with the chaser head whereby the chaser dies are retracted transversely at a uniform rate during their thread-cutting engagement to produce a thread of a desired taper. Such machines are well known in the art and several different designs are available. Of course, as previously mentioned, a slight modification of the chaser head must be made since the present invention contemplates use of sets of but two or three dies.

While I have shown and described certain specific embodiments of my invention, I do not wish to be limited exactly thereto except as defined in the appended claims.

I claim:

1. Carbide chaser dies adapted to be mounted in a retractable chaser head to cut a fully formed tapered thread running out at a steeper taper than the fully formed thread, said chaser dies having forward and rearward ends at least three and not more than four carbide thread cutting teeth spaced apart one pitch of the finished thread cut thereby, each of said teeth having a fully formed cut tangent to the vanish cone of the said finished thread, a leading flank-cutting portion and a following flank-cutting portion having flank angles equal respectively to the leading and following flank angles of the finished thread, said flank angles being greater than

$$\cos^{-1} \frac{.002}{.018}$$

the rearmost tooth only having a crest-cutting portion disposed rearwardly of its following flank-cutting portion, said chaser being substantially free of flank contact rearwardly of the thread crest cut thereby, said crest-cutting and root-cutting portions of said rearmost tooth being tangent to the major and minor cones respectively of the said finished thread.

2. Carbide chaser dies adapted to be mounted in a retractable chaser head to cut a fully formed tapered symmetrical thread running out at a steeper taper than the fully formed thread, said chaser dies having forward and rearward ends and at least three and not more than four thread cutting teeth spaced apart one pitch of the finished thread cut thereby, each of said teeth having a fully formed root-cutting portion tangent to the vanish cone of the finished thread, a leading flank-cutting por-

tion and a following flank-cutting portion, the rearmost tooth having a crest-cutting portion extending rearwardly from its following flank-cutting portion, said chaser being substantially free of flank contact rearwardly of the thread crest cut thereby, said crest-cutting and root-cutting portions of said rearmost tooth being tangent to the major and minor cones respectively of the finished thread, the following flank-cutting portion and the leading flank-cutting portion of all the teeth having a flank angle equal to the half angle of the finished thread, said half angle being greater than

$$\cos^{-1} \frac{.002}{.018}$$

3. In apparatus for cutting a fully formed tapered thread of the desired pitch and depth having a runout of steeper taper than the taper of the fully formed thread portion on a cylindrical workpiece including a die head having a forward face adapted to receive the workpiece the combination therewith of a series of at least two but not more than three identical carbide chaser dies, each of said chaser dies having forward and rearward ends and at least three and not more than four carbide thread cutting teeth spaced apart one pitch of the finished thread cut thereby, each of said teeth having a fully formed root-cutting portion tangent to the vanish cone of said finished thread, a leading flank-cutting portion and a following flank-cutting portion, the rearmost tooth having a crest-cutting portion disposed rearwardly of its following flank-cutting portion, said chaser being substantially free of flank contact rearwardly of the thread crest cut thereby, said crest and root-cutting portions of said rearmost tooth being tangent to the major and minor cones respectively of the said finished thread, the following and the leading flank-cutting portions of all of said teeth having flank angles equal to those of said finished thread, said flank angles being greater than

$$\cos^{-1} \frac{.002}{.018}$$

each of said chaser dies being mounted in said head with its teeth extending inwardly therefrom and with each succeeding die positioned inwardly an additional amount equal to the depth of the said finished thread divided by the number of dies in the said series of chaser dies and with each succeeding die being displaced angularly and rearwardly, said rearward displacement being an amount equal to the pitch of the said finished thread multiplied by the ratio of the angular displacement to 360° .
